UNITED STATES PATENT OFFICE

113,566

DESIGN FOR AN AUTOMOBILE TRACTION DEVICE

Chester Le Roy Landis, Reading, Pa.

Application December 20, 1937, Serial No. 73,770

Term of patent 3½ years

To all whom it may concern:

Be it known that I, Chester Le Roy Landis, a citizen of the United States of America, residing at Reading, in the county of Berks and State of Pennsylvania, have invented a new, original, and ornamental Design for an Automobile Traction Device, of which the following is a specification, reference being had to the accompanying drawing, forming part thereof.

Figure 1 represents a perspective view of an automobile traction device, showing my new design, and

Figure 2 represents an end view of the device.

I claim:

The ornamental design for an automobile traction device, as shown.

CHESTER L. LANDIS.
